THREAD-TENSIONING DEVICE FOR CIRCULAR LOOM SHUTTLES

William Alexander Dickie and Frank Corbyn Hale,
Spondon, near Derby, England, assignors to
Celanese Corporation of America, a corporation
of Delaware

Application November 27, 1936, Serial No. 112,964
In Great Britain January 17, 1936

3 Claims. (Cl. 139—13)

This invention relates to thread-tensioning devices for circular loom shuttles and in particular for the weft spools of circular loom shuttles of the type shown in U. S. Patent No. 2,050,328 in which the weft is wound between two flanges of considerable diameter in relation to the axial depth of the spool.

According to the invention, the spool is held stationary and the weft is led over one flange of the spool by means of an annular guide co-axial with the spool and disposed so as to prevent contact of the weft with the spool flange. The weft is led substantially to the centre of the annular guide and then delivered to the fell of the cloth, the tension in the weft thus being largely determined by its deflection over the edge of the annular guide and at the centre of the guide.

The guide may be in the form of a light wire spider with its rim lying in the plane of the spool flange or even somewhat inside this plane; or, in order to make sure that contact with either the inside or the outside edge of the flange is avoided, the width of the annulus may be increased, as, for example, by forming it of two wires side by side.

The guide may be arranged to rotate so as to provide for low weft tension, this rotation being provided either by pivoting the guide about the centre of the spool or on an independent support. The weft may be caused to engage the annular guide positively so as to rotate the guide and add to the weft tension. This positive engagement may, however, be such as to permit the guide to over-run the weft, e. g. when weaving stops, as by the provision on the edge of the guide of a number of small hooks with which the thread engages as it rotates about the spool during unwinding, over-running of the guide releasing the weft from the hook with which it has become engaged. For this purpose the hooks are preferably arranged so that during such overrunning the weft may pass freely over the hooks.

In order to prevent weft that has become loose on the spool when weaving stops from leaving the spool and becoming snarled in the shuttle or mechanism connected therewith, as for example when crêpe or other twisted yarn is used, a box or casing may be disposed so as to surround the spool closely.

By way of example some forms of apparatus according to the invention will now be described in greater detail with reference to the accompanying drawing in which

Fig. 1 is a side elevation of a shuttle embody-

ing one form of apparatus according to the invention in association with the weft spool;

Fig. 2 is a cross-sectional elevation of part of the apparatus shown in Fig. 1;

Fig. 3 is a plan of a detail of Fig. 1;

Fig. 4 is a side elevation of a spool of the type shown in Fig. 1 and equipped with another form of apparatus according to the invention; and

Fig. 5 is a cross-sectional elevation of part of the apparatus shown in Fig. 4 viewed on line 5—5 of Fig. 4. Figs 2, 3 and 5 are drawn on larger scale than Figs. 1 and 4.

Referring to Figs. 1 and 2 the shuttle 6 carries by means of clips 61 a stationary weft spool 7 from which weft thread 8 proceeds through guides 9, 10 disposed on the shuttle to the fell 11 of the fabric.

The spool 7 is bored centrally to receive a bushing 12 (Fig. 2) which forms a bearing for a rotatable hollow spindle 13 of a weft unwinding and tensioning device. The device comprises a light wire spider consisting of arms 14 and a rim 15, the arms being radially supported by an outstanding flange 16 formed at the outer end of the hollow spindle 13 and being bent inwardly so as to hold the rim 15 substantially in the plane of the front flange of the spool 7.

At the commencement of weaving the weft thread 8 is led over the rim 15 of the spider and threaded through the hollow spindle 13 from the front to the rear of the spool, from whence the thread passes to the guides 9, 10 and to the fell 11 of the fabric. The weaving tension in the thread causes it to bear against the rim 15 in unwinding from the spool with the result that the spider rotates and guides the thread clear of the front flange of the spool. The direction of rotation of the spider 14, 15 is indicated by an arrow in Fig. 1.

In order to ensure that the thread 8 engages the rim 15 positively the rim is formed with outstanding hooks 18 at intervals round its periphery (see Figs. 1 and 3), any hook engaging the thread while allowing of free passage of the thread across the rim 15. The shanks of the hooks 18 are shaped in such a manner as to offer no resistance to disengagement of the thread 8 from a hook in the event of over-running of the spider 14, 15 upon stoppage of weaving, and the bases of the hooks merge smoothly into the rim 15 in order that the hooks may pass the thread freely without catching the thread during any such over-running of the spider. In this manner though the spider assists in unwinding the thread 8 during weaving any over-running of the spider

on stoppage of weaving does not cause the weft thread 8 to continue to unwind.

In order to tension the thread 8 and to reduce any tendency to over-running of the spider 14, 5 means are provided for furnishing a predetermined degree of resistance to rotation of the hollow spindle 13. Thus, the bore of the bushing 12 is of larger diameter near the flange 16 (see Fig. 2) to provide housing for a light compression spring 20 which encircles the hollow spindle 13 and bears at one end against the interior of the bushing 12 and at the other against the flange 16 of the hollow spindle, and in this manner exercises a braking effect on the spindle. The 15 hollow spindle 13 is held in position against the action of the spring 20 by means of a circular locking spring 21 which bears against a washer 22 and fits into a groove formed round the end of the hollow spindle. The bushing 12 is slotted 20 as at 24 and slightly expanded and sprung so as to grip the bore of the spool on being pushed into position in the bore. The resistance to rotation of the hollow spindle 13 (and hence the degree of tension in the thread 8) may be varied 25 by changing the spring 20 for one of different strength.

In Figs. 4 and 5 a spool 25 having a non-rotating weft unwinding guide in the form of a light wire spider is shown. The spool 25 is bored centrally to receive a hollow core 26 which is fixed in the bore of the spool by a locking spring 27 and a co-operating washer 28 disposed at the inner end of the core. The core 26 holds a tube 29 of porcelain or the like which guides the 30 thread smoothly from the front to the rear of the spool. The core 26 is formed at its outer end with a flange 30 which supports radially disposed arms 31 carrying at their ends a pair of similar rims 32. The rim-carrying ends of the 35 arms 31 are bent inwardly towards the spool so as to hold the rims 32 coaxial with the spool and on opposite sides of the space bounded by the planes occupied by the inner and outer surfaces of the front flange of the spool 25.

40 At the commencement of weaving the weft thread (designated by 33 in Fig. 4) is led over the rims 32 and threaded through the tube 29 from the front to the rear of the spool 25. The 45 weaving tension in the thread causes it to slip round the rims 32, the disposition of which ensures that the thread is guided clear of the inside and outside surfaces of the outer flange of the spool.

In order to prevent too free passage of the 50 thread 33 round the rims 32, and to prevent ex-

cessive over-running of the thread on stoppage of weaving, a length of furry material 34 such as closely cropped sheepskin or catskin is disposed so as to contact with the rims 32 and consequently with the thread as it slips round the rims. The fur is secured to a curved support 35 which is suitably attached to the shuttle.

While in Fig. 4 the fur 34 is shown contacting with a portion only of the peripheries of the rims 32 it will be understood that when weaving a 10 weft of a type which tends to snarl or unwind from the spool too freely, e. g., a crêpe weft, fur can be arranged to contact with the entire periphery of the rims 32. Again, while a double rim 32 of the type shown in Figs. 4 and 5 has been 15 described in connection with a stationary weft unwinding spider, it will be understood that such rim could be provided on a rotatable spider of the type shown in Figs. 1 and 2. Similarly the double rims 32 of Figs. 4 and 5 could be replaced 20 by a single rim of the type shown in Figs. 1 and 2.

Having described our invention what we desire to secure by Letters Patent is:—

1. A circular loom shuttle comprising a circular 25 weft spool having flanges of considerable depth, means for holding said spool stationary in the shuttle, an annular guide disposed coaxially with the spool and adapted to prevent thread unwinding from the spool from contacting with a flange 30 of the spool; and means co-operating with said guide for restraining too free passage of the thread round the guide.

2. A circular loom shuttle comprising a circular 35 weft spool having flanges of considerable depth, means for holding said spool stationary in the shuttle, a core fixed in said shuttle, arms extending radially outwards from said core, a pair of annular guides supported side by side by said arms coaxially with the spool and on opposite 40 sides of the space bounded by the planes occupied by the surfaces of a flange of the spool so as to prevent thread unwinding from the spool from contacting with said flange, and means co-operating with said guides for restraining too 45 free passage of the thread round the guides.

3. A weft spool for circular loom shuttle comprising an annular guide disposed co-axially with the spool and adapted to prevent thread unwinding from the spool from contacting with a flange 50 of the spool, and means co-operating with said guide for restraining too free passage of the thread round the guide.

WILLIAM ALEXANDER DICKIE.
